UNITED STATES PATENT OFFICE.

HERMANN OTTO RISSE, OF LEIPSIC, GERMANY.

SPIRIT-LEVEL.

SPECIFICATION forming part of Letters Patent No. 508,762, dated November 14, 1893.

Application filed May 10, 1893. Serial No. 473,681. (No model.)

To all whom it may concern:

Be it known that I, HERMANN OTTO RISSE, a subject of the Emperor of Germany, residing at Leipsic, in the Kingdom of Saxony, 5 German Empire, have invented certain new and useful Improvements in Spirit-Levels, of which the following is a full, clear, and exact specification.

This invention has for its object to provide 10 a new and improved spirit level which may be used the same as ordinary spirit levels; and also for indicating the inclination of other than plane surfaces, such for example as shafts or cylinders.

15 To accomplish this object my invention consists in the features of construction and the combination or arrangement of devices hereinafter described and claimed, reference being made to the accompanying drawings, in 20 which—

Figure 1 is a plan view of a spirit level constructed in accordance with my invention. Fig. 2 is a sectional side elevation of the same; and Fig. 3 is a plan view showing the end sections adjusted out of coincidence with the 25 body of the spirit level.

In order to enable those skilled in the art to make and use my invention, I will now describe the same in detail, referring to the 30 drawings, wherein the letters *a*, and *b* indicate two spirit tubes fixed at right angles to each other in the body of the instrument, which latter is constructed of malleable iron, or some other material capable of resisting shocks or

35 strains. The main tube *a* is preferably placed within the body of the instrument, so that it is visible through openings at the top and each side of a cover plate *c*, and the secondary tube *b* is visible from both sides of the instrument. The openings to both tubes may be covered by disks, plates, or pieces of glass to shield and protect the tubes.

The sides and the top and bottom of the body of the instrument are rectilinear and 45 parallel to the main tube *a*; and the end sections *d'*, *d''* on the body of the instrument are parallel to the secondary tube *b*. The end sections *d'*, *d''* are grooved at their three outer or exposed sides, as indicated at *f*, *f'*, and 50 these end sections are susceptible of move-

ment upon the extremities of the body of the instrument.

In Fig. 1 the end sections *d'*, *d''* are shown in their normal positions, while in Fig. 3 they are shown adjusted laterally out of coincidence with the body of the instrument. The lateral adjustment of the end sections is accomplished through the medium of rotatable screws *g* *g'*, journaled to rotate in the end portions of the body of the instrument and 60 engaging screw nuts *e* *e'* which are rigidly fixed in any suitable manner to the laterally adjustable end sections *d'* *d''*. It is very desirable that both end sections be adjusted to the same degree, for the purpose of obtaining 65 parallelism of the main tube *a*, and the cylindrical or other surface being tested; and to accomplish this object I provide spring-controlled pins *k* and *k'*, which are mounted on the body of the instrument, and are provided 70 with finger pieces *r* *r'*, by which they may be drawn outward to disengage the inner ends of the pins from recesses or holes in the inner sides *h* *h'* of the end sections *d'*, *d''*. When the end sections are adjusted laterally through 75 the medium of the screws *g* *g'*, the spring-pressed pins will spring into the recesses or holes in the inner sides *h* *h'* of the end sections, so that the latter can be adjusted to the same extent. The grooved construction of adjustable end pieces enables these parts to rest firmly upon any shaped surface, as for instance a shaft or cylinder.

Having thus described my invention, what I claim is—

1. A spirit level having laterally adjustable end sections, one or more, substantially as described.

2. A spirit level having laterally adjustable end sections provided with grooves, substantially as described.

3. The combination with the body of a spirit level, of laterally adjustable end sections carrying screw nuts, and screws mounted on the body of the instrument and engaging the screw nuts for adjusting the end sections laterally, substantially as described.

4. The combination with the body of a spirit level, of laterally adjustable end sections, means for adjusting the end sections, and

spring-pressed pins adapted to snap into engagement with the adjustable end sections, substantially as described.

5. The combination with the body of a spirit level, of laterally adjustable end sections provided with grooves and carrying screw nuts, screws mounted on the body of the instrument and engaging the screw nuts for adjusting the end sections, and spring-pressed pins

carried by the body of the instrument and adapted to snap into engagement with the end sections, substantially as described.

In witness whereof I have hereunto set my hand in presence of two witnesses.

HERMANN OTTO RISSE.
